COLLAR STAY

Charles Andrew Doric, West Warwick, R. I.

Application July 9, 1951, Serial No. 235,811

3 Claims. (Cl. 2—132)

1

This invention relates to a collar stay for supporting the wings of a soft collar in proper position.

The object of the invention is to provide a collar stay which may be made without the use of a machine and at a comparatively low cost yet durable and satisfactory in use.

With these and other objects in view, the invention consists of certain novel features of construction, as will be more fully described and particularly pointed out in the appended claims.

In the accompanying drawings:

Figure 1 is a perspective view of a shirt collar with collar stays embodying my invention attached to the two wing portions of the collar;

Figure 2 is a sectional view taken substantially along line 2—2 of Figure 1 with the inner band of the collar omitted showing the collar stay attached to the inner layer or facing of the collar;

Figure 3 is a plan view of a strip of core material;

Figure 4 is a plan view of the core shown in Figure 3 covered with a textile fabric;

Figure 5 is a similar view to that shown in Figure 4 but with the strip severed in half providing two similar portions;

Figure 6 is a plan view of one of the portions shown in Figure 5 provided with collar-engaging pointed elements;

Figure 7 is a similar view showing the collar-engaging pointed elements as being additionally secured in place by means of narrow bands wound about the body of the collar stay;

Figure 8 is a view similar to that shown in Figure 6 but showing a modified construction of collar-engaging elements;

Figure 9 is a sectional view taken substantially along line 9—9 of Figure 7;

Figure 10 is a plan view of the collar-engaging element; and

Figure 11 is a plan view of a fragmental portion of a band material prior to assembling the same on the collar stay as shown in Figure 7.

In carrying out my invention I make use of a strip 10 of a pliable material which is for curling hair. The strip 10 is tapered at each end, as shown in Figure 4, and comprises a metallic core 11 shown in Figure 3 which is made of a malleable metal. This core 11 has braided or otherwise provided thereon a tubular covering 12 which tightly embraces the said core 11. The braid may be made of any suitable material usually used for this purpose, such as natural or synthetic fibers as cotton, rayon, or other material suitable for such use. This strip 10 is severed

2

in half, providing two similar portions 13 tapered at one end as at 14 and which portions provide a pair of stay member bodies 16.

A collar-engaging pointed element 17 shown in Figure 10 has the non-pointed end portion thereof bent or turned at right angles as shown to provide a head 18 or the said head may be provided by bending the end portion into a T formation or upset as in a common pin as shown at 18' in Figure 8. One such element is inserted between the core and the said braided material so as to position the pointed end thereof beyond each end extremity of the body 16. The element 17 which is positioned at the tapered end of the body 16 extends beyond the end extremity to a greater extent than the element 17' at the other end of the body 16. In inserting the element 17 in place between the core and the braid, the head 18 will provide a limiting abutment upon insertion by engaging the material at the point of insertion of said element therethrough.

In inserting the element 17 between the braid and the core, the braid will be additionally tensioned and tightly hold the element 17 onto the core to secure said element in place. The element is further secured in position by means of a narrow band 20 which may be an adhesive tape of a cellulose material which is wrapped about the body to engage and enclose the said head 18 of the element.

In applying the collar stay in place the tapered end portion thereof is positioned beneath the collar 21 at the pointed ends 22 thereof. The element 17 at this tapered end is inserted into the seam of the collar to provide a secure attachment thereto and the element 17' at the other end of the stay is inserted into the inner layer or facing 23 of the collar and is prevented from penetrating the outer layer of the collar by means of the end 24 of the body engaging against the said facing.

I claim:

1. A collar stay comprising an elongated member having a flat strip relatively stiff core with a textile fabric covering tightly embracing said core, a collar-engaging pointed element at the end portion of said member with its point extending beyond the member and located between said covering and core in secure frictional engagement therewith, said element having a head positioned outwardly of the covering, and a narrow band tightly encircling said member and said element at the location of said head for additionally securing the said element in place,

2. A collar stay as set forth in claim 1 wherein said covering is a braided tubular fabric.

3. A collar stay comprising an elongated member having a flat strip metal core tapered at one end, a braided tubular textile fabric tightly embracing said core, a collar-engaging headed element having a pointed end and extending between said covering and core in secure frictional engagement therewith, with the head of said element positioned outwardly of said covering and in engagement therewith and the pointed end of said element extending beyond the end of said member, and an adhesive tape encircling said mem-

ber at the portion thereof containing the head of said element for securing the said element in place.

CHARLES ANDREW DORIC.
